ANTHONY BIZZARRI, OF NEW YORK, N. Y.

DEVICE FOR FORMING NOODLES, SPAGHETTI, AND THE LIKE

Application filed December 30, 1930. Serial No. 505,474.

My present invention relates to apparatus for manufacturing spaghetti and the like, and aims to devise apparatus of the general character specified which is simple in construction, which may be readily and conveniently fabricated and assembled, and which is highly simple, convenient and expeditious in operation, its operation being characterized by such simplicity as to permit 10 the devices of the present invention to be utilized for domestic purposes, in restaurants and elsewhere for the purpose of making spaghetti and the like fresh and to order as desired by the customers. Other objects and 15 advantages of the devices of the present invention, particularly as exemplified in the following illustrative embodiment of the same, will in part be pointed out hereinafter and will in part be readily apparent to those 20 skilled in the art to which the present invention relates.

In the accompanying specification I shall describe and in the annexed drawing more or less diagrammatically exemplify one illustrative embodiment of the apparatus of 25 the present invention. It is, however, to be clearly understood that my invention is not limited to the specific embodiment thereof herein shown and described for purposes of 30 illustration only.

Referring to the drawing, in which I have more or less diagrammatically shown the aforesaid illustrative embodiments of the apparatus of the present invention:

35 Fig. 1 is a side elevational view, partly broken away to make the showing clearer, of the aforesaid illustrative embodiment of the apparatus of the present invention; and

40 Fig. 2 is a top plan view of the form of the invention shown in Fig. 1 of the drawing.

Referring now to the aforesaid illustrative embodiment of the present invention and with particular reference to the drawing showing the same, 10 indicates a base or a pedestal for the apparatus as a whole, the same being dished-out as at 11 for the reception of a bowl or other receptacle 12 which is to receive the spaghetti or other product resulting from the operation of the device 50 shortly to be described.

14 indicates a standard which is associated with the base 10, as by being made integral therewith, the standard being provided with a collar 15 for receiving the motor housing 16 within which is the electric or other motor 17 for providing the source of power needed for the operation of the device shortly to be described. The motor housing 16 is provided with the inner wall 18 which provides one of the walls for the hydraulic fluid reservoir 19 which preferably contains a lubricating or similar oil which will not have a tendency to rust or otherwise harm the various operative parts of the device. 20 designates the motor shaft which carries at its inner end within the fluid reservoir space 19 the eccentric 21. 22 is an electric or similar switch the manipulation of which serves to put the electric motor 17 into or out of operation as desired.

23 designates an extension of the hydraulic fluid casing 24 with which the various operative parts of the device are associated. For this purpose the part 23 may have the cylindrical extension 25 which constitutes a hydraulic cylinder within which reciprocates the hydraulic piston 26. The head 26' of the piston 26 is normally kept in operative contact with the outer surface of the eccentric 21 by means of the coil or equivalent compression spring 27 which serves by the expansion force inherent in it to maintain the piston 26 in operative contact with the surface of the eccentric 21. For this purpose, the upper end of the compression spring 27 may abut against the under surface of a member 28 carried by the hydraulic piston 26. Similarly the lower end of the compression spring 27 may bear against the surface 29 defining a portion of the part 23.

30 indicates an outlet for hydraulic fluid from the reservoir 19 into the space 31 beneath the piston 26. Passage of the hydraulic fluid through the port 30 into the space 31 and out of such space is controlled by the check valve which may, for example, comprise the ball valve 33 and the coil compression spring 34 which, by reason of the expansive force inherent in it, normally forces the ball valve 33 against the seat 35 formed

on the lower portion of the part 23 below the hydraulic cylinder 25. The expansive force of the spring 34 which serves to keep the ball valve 33 against the seat 35 may be regulated 5 by means of the screw cap 36 which is externally threaded at its inner end for cooperation with a similarly internally threaded portion of the part 23 and whose operation further into or out of the part 23 serves to regulate 10 the expansive force which the coil compression spring 34 exerts against the ball valve 33 pressing the same against the seat 35.

37 is a port communicating with the space 31 by way of the check valve 33 and the space 15 38 surrounding the coil compression spring 34. The port 37 in turn communicates with the lateral port 38' which in turn communicates with the upper port 39 communicating with the cylinder space 41 within the hydraulic cylinder 42 above the hydraulic piston 43 adapted to reciprocate within the hydraulic cylinder 42.

The hydraulic piston 43 is carried by a piston rod 44 which at its other end carries the 25 forming piston 45 which is on the lower side of the piston head 46. Surrounding the piston rod 44 is a coil compression or other spring 47 the upper end 47' of which bears against the under surface of the hydraulic 30 piston 43 and the lower end 47' of which bears against the upper surface of the partition 46' surrounding the part 46'' which forms a part or extension of the piston head 46.

35 In a sense forming an extension of the hydraulic cylinder 42 is the forming cylinder 48 which is hinged as at 49 to the lower portion of the hydraulic cylinder 42 and within which, when the forming cylinder 48 is in place, the forming piston 45 is intended to reciprocate. 50 is a handle for manipulating the forming cylinder 48 which is provided with the hook portion 51 for cooperation with the pin 52 for locking the forming cylinder 48 in place for the forming operation which will shortly be described. The lower end 53 of the forming cylinder 48 is provided with the perforations 54 through which the 50 dough or equivalent material is forced in the formation of the spaghetti or other material which it is the object of the devices of the present invention to produce. It will therefore appear that the forming cylinder 48 and particularly the lower end 53 thereof provided with the perforations 54 serves as a sort of forming die.

60 This completes the description of the aforesaid illustrative embodiment of the present invention. The structure of such embodiment and the mode of assembling the same will, it is submitted, clearly appear from the foregoing description. Likewise the manner of operating said embodiment will, it is submitted, clearly appear from the

foregoing description but may be briefly summarized as follows:

Assuming that the device is in the position of its various parts illustrated in Fig. 1 of the drawing, the forming cylinder 48 is swung into open position by the manipulation of the handle 50, thus to unhook the portion 51 from the securing pin 52. The space 48' within the forming chambers 48 may now be either partially or completely filled with dough or other material and the forming chamber 48 may be swung back into forming position by the reverse manipulation of the handle 50 thus pulling the hook 51 to the securing pin 52. This loading operation having been completed, the switch 22 may now be manipulated to close the circuit through the electric motor 17, thus causing the shaft 20 and the eccentric 21 carried at its inner end to rotate within the fluid reservoir 19. The rotation of the eccentric 21 causes the reciprocating of the hydraulic piston 26 which is kept in operative contact with the surface of the eccentric 21 by means of the expansive force inherent in the compression spring 27. The reciprocation of the piston 26 forces hydraulic fluid from the reservoir 19 through the port 30 into the space 31 and thence past the seat 35 and the ball valve 33 against the expansive action inherent in the spring 34 into the space 38 and thence into the outlet port 37. From the outlet port 37 the hydraulic fluid under pressure passes through the lateral port 38', thence through the port 39 into the cylinder space 41. Here the pressure of the hydraulic fluid urges the hydraulic plunger 43 against the expansive action of the compression spring 47 and thus to move the forming piston 45 downwardly in the forming receptacle 48 downwardly against the dough or equivalent material in the space 48'. The continued movement of the parts causes the forming piston 45 to force the dough through the perforations 54 in the lower surface 53 of the forming chamber 48. Thus the spaghetti or equivalent material will be formed and deposited in the bowl or other container 13.

It may here be stated that should the pressure of the fluid in the spaces 31, 38 and 41 and in the communicating ports 30, 37 and 39 become too great, such dangerous pressure may be relieved by the safety valve 55 which is in the nature of a check valve embodying the ball valve 56 pressing against the seat 57 adjacent the port 58 which communicates with the space 38'. Within the space 59 is a coil or equivalent compression spring 60 which by reason of the expansive force inherent in it serves normally to maintain the ball valve 56 against the valve seat 57. The action of the spring 60 may be controlled by means of the screw cap 61 which, by being screwed further into or screwed somewhat

out of the space 59, serves to regulate the expansive action of the spring 60. 62 is a port communicating with the space 50 and also with the fluid reservoir 19. It will thus be seen that if the pressure of the hydraulic fluid in the spaces 31, 38 and 41 and in the communicating ports 30, 37, 38' and 39 becomes excessive, fluid will pass into the port 58 past the ball valve 56 against the seat 57 against the expansive action of the inlet compression spring 50 thence into the port 62 and thence into the fluid reservoir 19.

When the cycle of operations described above has been completed, it is desired to release the hydraulic pressure in the space 41 and thus to restore the parts to their elevated or normal position for a fresh cycle of operations. For this reason I may provide suitable means, such as the fluid pressure releasing means 63 comprising the threaded stem 64 having at its outer end the knurled operating member 65 and at its inner end the valve member 66 cooperating with the seat 67 in the portion 68 of the hydraulic cylinder 42. 69 is a port communicating with the hydraulic cylinder space 41 and 70 is a port communicating with the liquid reservoir space 19, and two ports 69 and 70 communicating with each other by means of the space 130 between the valve 66 and the seat 67. It will therefore be seen that hydraulic pressure having been built up in the hydraulic cylinder space 41 by the operation of the device in the manner described above, such pressure may be released by the operation of the release 63, which will serve to put the port 69 and 70 into communication with each other, the space between the valve 66 and the seat 67 and thus to put the high pressure space 41 into communication with the low pressure reservoir fluid space 19, this action serving forthwith to restore the pistons 43 and 45 to their normal elevated position by reason of the expansive force inherent in the coil or equivalent compression spring 47 and thus to restore the parts to their normal position, for a further cycle of operations, assuming, of course, that the switch 22 has been turned off as soon as the desired formation of the 55 spaghetti or the like has been completed.

This completes the description of the mode of operation of the aforesaid illustrative embodiment of the present invention. It will be noted that such operation is simple, convenient and expeditious and is such as to enable any ordinary householder or any ordinary employee in a restaurant or the like to use the devices of the present invention with complete success.

Other superiorities and advantages of the devices of the present invention in mode of construction, mode of assembly, mode of operation and use will readily occur to those skilled in the art to which the present invention relates.

What I claim as my invention is:

1. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like and thereafter closed into operative position. 70

2. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, means for normally maintaining said hydraulic and forming pistons in positions ready for action, and forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like and thereafter closed into operative position. 90

3. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, means comprising a compression spring coiled about said piston rod between said hydraulic piston and said cylinder head for normally maintaining said hydraulic and forming pistons in positions ready for action, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like and thereafter closed into operative position. 105

4. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, means for normally maintaining said hydraulic and forming pistons in positions ready for action, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like, and thereafter closed into operative position in combination with motor operable means for applying hydraulic pressure to said hydraulic piston.
5. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like, and thereafter closed into operative position in combination with motor operable means for applying hydraulic pressure to said hydraulic piston.
6. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, means for normally maintaining said hydraulic and forming pistons in positions ready for action, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like, and thereafter closed into operative position in combination with motor operable means for applying hydraulic pressure to said hydraulic piston.
7. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like, and thereafter closed into operative position in combination with motor operable means for applying hydraulic pressure to said hydraulic piston, said motor operable means comprising a motor having a drive shaft, an eccentric carried by said drive shaft, a reservoir for hydraulic fluid, a hydraulic pump having a piston for actuation by said eccentric, and a cylinder for said piston in communication with said reservoir and with said hydraulic cylinder.
8. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like, and thereafter closed into operative position in combination with motor operable means for applying hydraulic pressure to said hydraulic piston, said motor operable means comprising a motor having a drive shaft, an eccentric carried by said drive shaft, a reservoir for hydraulic fluid, a hydraulic pump having a piston for actuation by said eccentric, and a cylinder for said piston in communication with said reservoir and with said hydraulic cylinder, together with valve-controlled means for establishing communication be-

ween said hydraulic cylinder and said reservoir.

9. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, means for normally maintaining said hydraulic and forming pistons in positions ready for action, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder 20 to permit the same to be swung clear of said hydraulic cylinder charged with paste or the like, and thereafter closed into operative position in combination with motor operable means for applying hydraulic pressure to 25 said hydraulic piston, said motor operable means comprising a motor having a drive shaft, an eccentric carried by said drive shaft, a reservoir for hydraulic fluid, a hydraulic pump having a piston for actuation by said eccentric, and a cylinder for said piston in 30 communication with said reservoir and with said hydraulic cylinder, together with valve-controlled means for establishing communication between said hydraulic cylinder and 35 said reservoir.

10. In a device for manufacturing spaghetti and the like, a hydraulic cylinder, a hydraulic piston within said hydraulic cylinder, a cylinder head closing one end of said hydraulic cylinder, a piston rod carrying said hydraulic piston adjacent one end thereof and passing through said cylinder head and carrying a forming piston adjacent the other end thereof, and a forming cylinder adjacent said hydraulic cylinder for receiving said forming piston, said forming cylinder having at least one portion of at least one of the walls thereof provided with forming perforations, said forming cylinder being hingedly secured to said hydraulic cylinder to permit the same to be swung clear of said hydraulic cylinder charged with paste or the like, and thereafter closed into operative position in combination with motor operable means for applying hydraulic pressure to said hydraulic piston, said motor operable means comprising a motor having a drive shaft, an eccentric carried by said drive shaft, a reservoir for hydraulic fluid, a hydraulic pump having a piston for actuation by said eccentric, and a cylinder for said piston in communication with said reservoir and with said hydraulic cylinder, together with manually operable valve-controlled means for establishing communication between said hydraulic cylinder and said reservoir.

In testimony whereof, I have signed my name to this specification this 6th day of Dec., 1930.
